CAP FOR FILL PIPES

Henry P. Wilking, Waldwick, N. J.

Application September 24, 1936, Serial No. 102,309

3 Claims. (Cl. 220—39)

This invention relates to a filling cap for gasoline tanks located below the ground as is common in filling stations, the cap being used for refilling the tank from tank wagons or cars, and has for its object to provide a cap which will readily disclose whether or not it has been tampered with.

Experience has shown there is danger of theft of gasoline from the storage tank, especially at night when the filling station is closed, by means of the cap on the supply tank being removed and a suction pipe placed down in the tank through the filling pipe. Suggestions have been made for locking the cap but such have often involved constructions which are bulky and rise too high above the ground, getting in the way of vehicles. Without a lock to reveal the fact that the device has been tampered with, the local law enforcement officer or officers may discount the loss in gasoline as having been due to a leak in the tank.

According to this invention, a lock is provided which does not cause any extension to rise an objectionable amount above the ground, and which offers a minimum danger of melting snow or ice getting into the gasoline tank. Specifically, the cap threaded on the upper portion of the filling pipe, has an integral extension rising above the top of the cap body and to which is pivoted a securing member for movement in a vertical plane to be raised from or lowered over said cap. There is also provided some locking means for holding the securing member down to prevent removal of a plug which is threaded into the cap.

Referring to the drawings, Fig. 1 is a top plan view of one embodiment of this invention.

Fig. 2 is a section on the line 2—2 of Fig. 1.

Fig. 3 is a top plan view of another embodiment.

Fig. 4 is a top plan view of a further embodiment of this invention.

Fig. 5 is a section on the line 5—5 of Fig. 4.

In Figs. 1 and 2 the usual filling pipe 10 extends from the gasoline storage tank to adjacent the level of the ground, and is provided on top with a cap 11 secured to the pipe 10 by the screw threads 13 illustrated. The cap 11 is internally threaded at 14 for reception of a closure or plug 12. A projection 15 on the cap extends above the top of the cap on one side, being provided with a pintle 16, to which is pivoted a securing member 17 adapted to be swung in a vertical plane. Within the securing member 17 is a recess 18 shaped as illustrated for cooperation with a projection 19 on the plug 12. A recess 20 is placed in the projection 19 at such a height that a padlock may

be passed through this recess when the securing member 17 is lowered over the projection 19, with the result that said securing member 17 can be held against being raised. The shape of the projection and recess is such that the plug 12 cannot be rotated while the securing member extends over its projection. The mouldable or cementitious material 21, such as the usual concrete sets around the cap 11 and prevents the cap from being unscrewed from the pipe 10. Around the peripheral top portion of the plug 12 is a flange illustrated beneath which may be placed suitable packing 22, to prevent melted snow or ice from getting to the screw threads 14 and leaking into the tank. Instead of the usual compressible packing, a substantially non-compressible material like ordinary cup grease has been found satisfactory, since it is adapted to flow or to be squeezed out when the plug is screwed down a half turn or more than is necessary to have the top of the plug substantially flush with the top of the cap.

In Fig. 3 the cap 11a is internally threaded as before to receive the plug 12a. The hinged support 15a for the securing member 17a may be held in position by the plate 23 which is held in position by means of a plurality of headed securing means 24 passing into the concrete 21a. As before, the securing member 17a is provided with a recess 18a fitting over a projection 19a on the plug 12a. Packing 22a of the same type as has previously been mentioned is used. Since in Fig. 3 the cap 11 does not have any integral projections, ribs 25 may be integrally formed on the outside of the cap 11a.

In the embodiment illustrated in Figs. 4 and 5 a second projection 28 is formed integrally on the cap 11b substantially diametrically opposite to the projection 15b. The securing member 17b is hinged at 16b in the projection 15b and is provided with the necessary recess 18b fitting over the second projection 28 so that a padlock shown in dotted lines may be passed through the recess 26 in the projection 28 for holding the securing member down over the plug or closure 12b. Spanner holes 27 in the top of the plug 12b provide a suitable means for applying a wrench to open or unscrew this plug 12b.

Under the peripheral flange of the plug in each embodiment illustrated may be used packing of any desired type, but preferably owing to the possibility that the securing member might be placed over the projection on the plug and rotated a half turn or more than was desired to bring the top of the plug and top of the cap 55

substantially flush, some type of packing capable of flowing, is preferred. For this purpose ordinary grease of a convenient viscosity has been found appropriate. Whenever the plug is taken out it will only be necessary to apply the grease to the screw threads of the plug and then as the plug is screwed home the grease can flow into the packing space 22b illustrated.

Among the advantages of this invention may be mentioned the provision of ribs on the outside of the cap constituted by the integral projection or projections for cooperation with the securing member. The padlock, if tampered with, will readily show such to be the fact. The cap and plug do not extend an objectionable amount above the top of the concrete, yet the filling opening is protected against theft and the entry of water into the supply tank. The construction illustrated in Figs. 4 and 5 is the preferred embodiment of this invention, while that shown in Fig. 3 is the least desirable of the several forms shown.

I claim:

1. The combination with a pipe leading to a subsurface tank, of a cap threaded over the upper end portion of said pipe, a plug threaded into said cap with a thread diameter at least about as large as that of the pipe, provided with a flanged top and adapted to be screwed down to a position with its top substantially flush with the top of said cap, a lug projecting substantially radially outward and upward from a side of said cap to above the top thereof, cementitious material surrounding said pipe and cap and substantially flush with the top surface of said cap, a securing member pivotally attached to said lug above the top of said cap and cementitious material but substantially contiguous the top of the cap and plug, and locking means for holding said securing member in position to prevent removal of the plug, a substantial portion of said lug extending below the top of the cap as a radial rib of depth greater than that of the top of said plug and cementitious material cooperating with said rib or lug to prevent rotation of said cap, and said lug extending only a short distance above the top of said cap, said lug or rib being also integral with and contiguous the top of the peripheral portion of the cap.

2. The combination with a pipe leading to a subsurface tank, of a cap threaded over the upper end portion of said pipe, a plug threaded into said cap with a thread diameter at least about as large as that of the pipe, provided with a flanged top and adapted to be screwed down to a position with its top substantially flush with the top of said cap, a lug projecting substantially radially outward

outward and upward from a side of said cap to above the top thereof, cementitious material surrounding said pipe and cap and substantially flush with the top surface of said cap, a securing member pivotally attached to said lug above the top of said cap and cementitious material but substantially contiguous the top of the cap and plug, locking means for holding said securing member in position to prevent removal of the plug, a substantial portion of said lug extending below the top of the cap as a radial rib of depth greater than that of the top of said plug and cementitious material cooperating with said rib or lug to prevent rotation of said cap and said lug extending only a short distance above the top of said cap, and another lug substantially opposite the first and substantially similar thereto, said securing member being recessed to allow the second mentioned lug to extend through it with said second mentioned lug and securing member cooperating with said locking means, each of said lugs being integral with and contiguous the top of the peripheral portion of the cap.

3. The combination with a pipe leading to a sub-surface tank, of a cap threaded over the upper end portion of said pipe, a plug threaded into said cap, with the diameter of the received portion of said plug being at least about as large as that of the pipe, provided with flanged top and adapted to be screwed down to a position with its top substantially flush with the top of said cap, a lug projecting substantially radially outward and upward from a side of said cap to above the top thereof, a substantial portion of said lug extending below the top of the cap and constituting a radial rib of greater depth than that of the top of said cap and plug, cementitious material surrounding said pipe and cap and substantially flush with the top surface of said cap, a securing member pivotally attached to said lug above the top of said cap but substantially contiguous the top of the cap and plug, locking means for holding said securing means in position to prevent removal of the plug, said lug extending only a short distance above the top of said cap, the top flange of said plug being laterally spaced, at least in part, from the recessed portion of said cap in which it is received, and fluid type packing under the top flange of the plug and within said cap, whereby said cap may always be screwed up to the desired amount flush with the top of said cap and a tight joint attained between it and the cap to keep out snow and ice forming therein, said lug or rib being also integral with and contiguous the top of the peripheral portion of the cap.

HENRY P. WILKING.
